US00D504667S

(12) **United States Design Patent** (10) Patent No.: **US D504,667 S**
(45) Date of Patent: **** May 3, 2005**

(54) **ELECTRICAL DEVICE**

(75) Inventors: **Gerald R. Savicki, Jr.**, Canastota, NY (US); **Kenneth D. Vought**, Syracuse, NY (US); **Yann Kulp**, Liverpool, NY (US)

(73) Assignee: **Pass & Seymour, Inc.**, Syracuse, NY (US)

(**) Term: **14 Years**

(21) Appl. No.: **29/213,062**

(22) Filed: **Sep. 13, 2004**

(57) **CLAIM**

The ornamental design for an electrical device, as shown and described.

DESCRIPTION

FIG. 1 is a perspective view of an electrical device showing our new design; and,

FIG. 2 is a front elevation view of the electrical device. In FIGS. 1 and 2, the broken line illustrations of the environmental structure form no part of the claimed invention.
